C. H. GRIFFIN.
Dressmaker's Chart.

No. 228,527.

Patented June 8, 1880.

UNITED STATES PATENT OFFICE.

CALEB H. GRIFFIN, OF BOSTON, MASSACHUSETTS, ASSIGNOR OF ONE-HALF
OF HIS RIGHT TO LEONARD F. WISE, OF SAME PLACE.

DRESS-MAKER'S CHART.

SPECIFICATION forming part of Letters Patent No. 228,527, dated June 8, 1880.

Application filed January 30, 1879.

To all whom it may concern:

Be it known that I, CALEB H. GRIFFIN, of Boston, in the county of Suffolk and State of Massachusetts, have invented certain new and useful Improvements in Dress-Makers' Charts, of which the following is a specification.

The object of my invention is to provide a cheap, simple, convenient, and durable device to be used in connection with the ordinary tape-measure in taking the dimensions of the various portions of the human body above the waist by actual measurement for the production of a pattern for use in cutting out garments; and it consists in the construction, combination, and arrangement of the several parts in outline or form, and providing such parts with certain "scales," lines, figures, divisions, and inches, or proportionate parts thereof, as hereinafter more fully described and set forth.

The accompanying drawing shows a perspective view of my invention.

A represents the body of the chart, having an irregular curved opening or slot, B, of the peculiar form shown, its convex edge portion C being provided with a "front arm size and neck" scale, graduated into inches and proportionate parts thereof, and indicated by figures from 1 to 10, inclusive, as shown, the first number or figure, 1, being placed one inch and a half from the short curved end of the opening nearest the top of the drawing, the lower pointed end being used to draw lines to form the "darts," and the other portions of the curved opening for drawing the various curved lines employed in cutting dresses, garments, &c., as heretofore employed, taken with the curve or concave outer edge marked "V under the arm." All curved lines required are so combined and arranged with the "square" or right-angle edges E and F, so as to save time and labor in turning and placing the device to draw the various lines in the pattern with that nicety or precision required to form a perfect-fitting waist or other portion of the garment without refitting, as heretofore required, wherein the drafting devices now in use are employed.

At the top right hand, near outer straight edge or line, will be seen the "front" arm scale, consisting of two scales placed equidistantly

one inch each side of the line marked X. 50 These scales consist of seventeen lines each, and are marked, respectively, 17 to 49, inclusive, omitting the alternate numbers.

The measurements by this "double scale" commence at the center line, (marked X,) one 55 inch, respectively, from the lowest number on each scale.

At the top left hand, near the corner, will be seen the "back neck" scale, and consists of seventeen lines, which are marked with figures 60 from 17 to 49, inclusive, omitting the alternate numbers. The spaces between the lines in this and the preceding "double scale" are one-eighth inch wide.

At the left-hand edge of the device, which 65 is formed on a straight line at a right angle to the line of the top or shorter side, will be seen "front neck" scale, and consists of thirty-four lines, half being short lines. The longer lines are marked with figures from 17 to 49, inclusive, 70 omitting the alternate numbers, the spaces between the lines being one-eighth of an inch wide. This scale and the two previous ones are marked, also, with figures from 4 to 12, inclusive, as shown. Below this scale, upon the 75 same line or extended edge, will be seen the "back and front waist" scale, consisting of thirty-two lines, marked with figures from 16 to 46, inclusive, omitting the alternate lines and alternate numbers, the spaces between the 80 lines being three-sixteenths of an inch, and is used to determine the relative size to be given to that portion or part of the garment which is at the "front" and at the "back" of the side seam at the waist. 85

Commencing at the lower corner or point of the device, the remaining edge or outline, marked "Bias-cutter," is formed on an angle of forty-five degrees with the last named or described vertical edge, and extending upward 90 on a straight line to the lower point of the concave edge, marked "V under the arm." This acute-angle edge is marked with inches and divisions and figures from 1 to 16, inclusive, as usual, and is designed to facilitate the cutting of cloth on the bias. The desired width of the ruffle or fold is measured and marked on the cloth; then the longest straight edge 95

of the device or chart is placed on the cloth in a line parallel either with the warp or weft of the same. The graduated lines on the "bias-cutter" show the exact gage of the desired 5 width of the ruffle.

Inwardly from the two straight right-angle edges I mark the usual inches and subdivisions, with the figures denoting the inches, as heretofore employed upon rules, squares, and 10 the like measuring devices.

This device or chart, with all its marks, lines, and figures, may be drawn upon stone, then lithographed upon sheets of paper of the desired size, or upon pasteboard, card-board, or 15 other desired material, which may be formed or cut to the outline shown, then the edges bound with sheet metal, as heretofore employed for shoe-patterns. By this means I am enabled to produce a very superior device or chart 20 at little expense, which is very light and easily placed in the desired position for drafting a pattern, and is free from many objections found in squares constructed in whole or part of wood and intended for similar purposes.

25 Having thus described my invention, what I claim is—

1. As an improved article of manufacture, a

dress-maker's chart consisting of the device shown, having the irregular curved opening B, its convex portion C being graduated and marked "Front arm size and neck," and its outer edge E being provided with the scales marked "Front arm size" and "Back neck," and the right-angle edge F being provided with the scales marked "Front neck" and "Back and front waist," and the edge G being graduated and marked "Bias-cutter" and formed on an angle of forty-five degrees with the edge F, and the edge H being formed slightly concave, and marked "V under the arm," all being 40 marked with figures and graduated as shown and described, as and for the purposes set forth.

2. In a dress-maker's chart, a form consisting of two straight right-angle edges and an edge formed at an angle of forty-five degrees, 45 and an edge, slightly concave, extending from the latter to one of the former, so as to complete the outline shown, and having an irregular curved opening, substantially as described, as and for the purposes set forth.

CALEB H. GRIFFIN.
